COMBINED ASHTRAY AND CIGARETTE LIGHTER OR SIMILAR ARTICLE

Samuel J. Koch, ½ Korex Industries, 821 Malcolm
Road, Burlingame, Calif.

Filed Sept. 17, 1971, Ser. No. 181,654

Term of patent 14 years

Int. Cl. D27—03

U.S. Cl. D85—2 L

FIG. 2

FIG. 3

FIG. 4

FIG. 5

FIG. 1 is a top plan view of a combined ash tray and cigarette lighter or similar article, showing my new design with the lighter in its well;

FIG. 2 is an exploded side elevational view looking from the plane of the line 2—2 in FIG. 1 in the direction of the arrows, with the lighter removed from its well, the opposite side being substantially a mirror image thereof;

FIG. 3 is a bottom plan view;

FIG. 4 is an exploded cross-sectional view partly in side elevation taken along the line 4—4 in FIG. 1; and

FIG. 5 is an exploded top and side perspective view thereof.

I claim:

The ornamental design for a combined ashtray and cigarette lighter or similar article, as shown and described.
